UNITED STATES PATENT OFFICE.

WILLIAM H. RICHARDSON, OF HUNTINGTON, WEST VIRGINIA.

CAR-ACTUATED SWITCH.

1,322,345.

Specification of Letters Patent.

Patented Nov. 18, 1919.

Application filed October 13, 1917. Serial No. 196,398.

To all whom it may concern:

Be it known that I, WILLIAM H. RICHARDSON, a citizen of the United States, residing at Huntington, in the county of Cabell 5 and State of West Virginia, have invented certain new and useful Improvements in Car-Actuated Switches, and that I do hereby declare the following to be a full, clear, and exact description of the invention, such 10 as will enable others skilled in the art to which it appertains to make and use the same.

This invention has for its object to provide an improved switch and car-carried 15 operating means therefor which may be conveniently controlled by the motorman or engineer.

Another object is the provision of a car-carried switch operating mechanism consisting 20 essentially of two independently movable frames which are normally retained in elevated position and carry wheels for engaging and shifting a bar controlling the switch points.

With these and other objects in view, the 25 invention consists in the novel construction, combination and arrangement of parts as will be hereinafter specifically described, claimed and illustrated in the accompanying drawings, in which:

Figure 1 represents a fragmentary side elevation of a car, illustrating the invention applied to use,

Fig. 2 represents a fragmentary bottom 35 plan view of a car,

Figs. 3 and 4 represent plan views of the switch in closed and open positions,

Fig. 5 represents a vertical sectional view 40 through one of the car-carried actuating devices engaged with the switch controlling bar,

Fig. 6 represents a detail sectional view on the line 6—6 of Fig. 2, and

Fig. 7 represents a bottom plan view of a 45 car illustrating a modified form of the invention.

Referring to the drawings in detail wherein similar reference numerals indicate corresponding parts throughout the 50 several views, the numerals 8 indicate the main track rails associated with the rails 9 of a switch. A portion of one of the rails 8 of the main track is taken out to accommodate one of the switch points 10, 55 which is pivotally secured at 11, and when moved into alignment with the track rails

permits a train to pass over the switch along the main track. The other switch point 12 is pivotally secured at 13, and is adapted to engage the other rail of the main track to 60 cause the train to take the siding. The two pivoted switch points 10 and 12 are connected by the connecting rod 14, whereby they are moved in synchronism.

A guide consisting of a base plate 15 and 65 upstanding flanges 16 is arranged between the main track rails 8 at a point adjacent the switch points 10 and 12, and the opposite ends of the flanges 16 are flared outwardly, as indicated at 17, for a purpose 70 which will hereinafter appear. A switch throwing bar 18 is pivotally secured at its end opposite the switch points 10 and 12, as indicated at 19, to the base plate 15, and the opposite end of the bar is connected by 75 a rod 20 with the switch point 10, whereby the latter is moved during oscillation of the bar 18 to open and close the switch.

The pivoted terminal of the bar 18 is located centrally between the guide flanges 80 16, providing a base 21 on either side for the reception of the actuating wheel carried by the moving train, and the bar 18 is preferably increased in width from its pivoted end to its free swinging end. 85

The mechanism for shifting the bar 18 to open and close the switch is illustrated in detail in Figs. 1 and 2 as applied to a conventional type of car including the wheel-mounted truck 23 and frame 24 supporting 90 the platform 25 and body structure 26.

A hinge rod 27 is supported in brackets 28 beneath the front end of the platform 25 and supports a pair of substantially U-shaped frames 29, which are arranged in 95 relatively close relation and are located on opposite sides of the longitudinal axis of the car in a position directly overlying the pivoted bar 18. Each frame is normally retained in elevated position directly under the 100 car frame 24 by the tension of coil springs 30, anchored at one end in fasteners 31 carried by the platform 25. The opposite ends of the springs are secured in the legs of the frame 29. The web portions of the frames are connected with compressible rods 32, which project through the platform 25 and provided with pedals 33 arranged in such position as to be conveniently depressed by the motorman or engineer operating the car. 105 110

A shaft 34 is journaled in the parallel legs of each frame adjacent the web and slidably

and rotatably supports a bar-actuating wheel 36, the rim of which is of such width as to fit between the pivoted terminal of the bar 18 and the adjacent portion of one of the guide flanges 16. The wheel is normally retained in uniformly spaced relation between the legs of the U-shaped frame by springs 37, which are designed to accommodate the usual swaying motion of the car during travel so as to prevent breakage or injury to the parts of the switch throwing mechanism during contact of the wheel between the bar and guide flange. As will be understood, the two frames 29 are arranged in such relation that, when depressed, the wheels 36 are projected into one or the other of the passages 21 on opposite sides of the bar 18, according to which of the frames is depressed.

Assuming that the switch is closed, as illustrated in Fig. 3, and a car approaching from the right is instructed to take the siding, the motorman depresses the left-hand frame 29 and as the car approaches the bar 18, the left-hand wheel 26 rolls upon the base plate 15 between the left-hand guide flange 16 and the bar 18, and as the car approaches the switch the wheel gradually throws the bar to the right and actuates the two switch points 8 and 10 through the connecting rods 20 and 14, moving said points to the position illustrated in Fig. 4. A car

approaching from the left on the main track automatically actuates the switch points to close the track ahead.

In the modification of the invention illustrated in Fig. 7, the pivoted wheel-carrying frames 29^a are normally held in elevated position by leaf springs 30^a, which are suitably fastened beneath the car body 24^a and the switch throwing bars in both types are preferably provided with a circumferential bevel.

What I claim is:

A switch throwing mechanism adapted for attachment to a car, comprising, a shaft; a U-shaped frame having parallel legs pivotally secured at their rear end portions to said shaft; a coil spring arranged on the shaft and adapted to normally retain the frame in elevated position; a cross shaft carried by the U-shaped frame; a wheel carried by said cross shaft for contact with the switch-throwing rod of a switch; coil springs arranged on said cross shaft on opposite sides of said wheel; and means to operate said frame to engage said wheel with said switch-throwing rod.

In testimony whereof I affix my signature in presence of two witnesses.

WILLIAM H. RICHARDSON.
